UNITED STATES PATENT OFFICE.

ROBERT W. WILLSON, OF NEW HAVEN, CONNECTICUT.

COMBINED TELEPHONE AND TIME SYSTEM.

SPECIFICATION forming part of Letters Patent No. 308,225, dated November 18, 1884.

Application filed February 23, 1884. (No model.)

To all whom it may concern:

Be it known that I, ROBERT W. WILLSON, of New Haven, in the county of New Haven and State of Connecticut, have invented a new 5 Improvement in Combined Telephone and Time System; and I do hereby declare the following, when taken in connection with the accompanying drawings and the letters of reference marked thereon, to be a full, clear, and 10 exact description of the same, and which said drawings constitute part of this specification, and represent, in—

Figure 1, the arrangement of a central office of a telephone system with apparatus for arresting the alternating currents and making continuous currents at predetermined times; Fig. 2, a detached view showing the arms *n* as they are arranged with relation to the armature of a multiple relay; Fig. 3, a top view, 20 and Fig. 4, a side view, of the station apparatus for receiving the alternating or continuous currents, as the case may be; Fig. 5, a modification.

This invention relates to a device to be used 25 in combination with a telephone system, whereby from the main office standard time may be communicated to the several stations, either by giving a predetermined signal at certain intervals or by connection with the synchronizing mechanism of a clock to set the pointers at such predetermined time; and the invention consists, generally, in charging the lines at predetermined intervals with a continuous current from the central office through 30 an apparatus at the several stations affected by such continuous currents to produce certain signals, but not affected by the ordinary alternating currents used for calling either the station or the central office.

40 In Fig. 1, I represents the central office of a telephone system of four circuits, *a b c d* representing the four drops on the annunciator. To these come the lines, respectively, *A B C D*, the line *E* representing the ground.

45 *F* is an armature-lever working between the two contacts *e f*, drawn to the contact *e* by a suitable spring, *g*. This armature-lever is grounded, as shown, so that when it stands against the contact *e* the circuit is made through 50 the annunciator or switch-board in the usual

manner, and the system is working as a telephone system. Upon the side of the armature-lever *F*, opposite the contact *e*, a magnet, *G*, is arranged, which, when in circuit, will attract the armature-lever, break the contact 55 *e*, and make the contact *f*. From the magnet *G* one wire, *h*, runs to the magnets *H*, thence, with a local battery, to the principal or central-office clock *I*. The other line, *i*, comes from the clock to the magnet. One wire, *l*, of the 60 battery *L* is in connection with the armatures *M* of the magnets *H*. The other wire, *m*, from the battery runs to the contact *f*. The clock *I* is provided with any of the many known devices for closing the circuit and holding it 65 closed for a short space of time at predetermined intervals. The device for closing the circuit between the wires *H* and *I* in the clock is not shown; but such devices are too well known to require particular description, it 70 only being essential that there shall be some device in the clock to close the circuit at the said predetermined times. When at such predetermined time the clock closes the circuit, the armature-lever *F* is instantly attracted to 75 the magnet *G*, taking it from the contact *e*, and bringing it upon the contact *f*, which at once cuts off the ground through the switch-board. At the same time the magnets *H* attract the said armatures *M*.

As shown, the two armatures *M* are connected by a bar, *N*. Above this bar springs or arms *n* are arranged in number corresponding to the telephone circuits or wires *A B C*, and from each of these arms *n* a wire, *p*, which 85 may include resistance to equalize the line, runs into connection with the respective lines *A B C D*. These arms or springs *n*, when the circuit through the magnets *H* is broken, stand above the bar *N*; but as that bar rises with the 90 armatures it makes contact with the several springs, as seen in Fig. 2. The current from one pole of the battery *L* passes out through the lines, the other pole being in connection with the armature-lever *F* to the ground. So 95 soon as the clock breaks its circuit at the termination of said short space of time, the armature-lever *F* breaks from the contact *f* and makes with the contact *e* and restores the switch-board into its usual condition, it being 100

80

understood that the space of time during which the contact is made through *f* is of sufficient duration to give the required signal, or to synchronize the clock, if that be the device by 5 which the time is given.

Through the telephone-circuits the current is the alternating current; but during the said interval the current will be continuous. Now, if a device be applied at the several stations 10 which is affected by the continuous current, but not affected by the alternating currents, it follows that the making and breaking of the circuit by the clock at the central office will act upon that device, while the ordinary 15 call-signals will not produce the time-signals. Such a device I show in Figs. 3 and 4.

P is the armature-lever of an ordinary polarized relay, so adjusted that when no current is passing it is necessarily against the 20 stop 3. This is accomplished by the use of a spring, as shown, or by adjusting the lever *P* between the stops 3 4, so that when it stands against the stop 3 the face of the armature on that side of the lever will stand nearer to its 25 pole than does the opposite face of the armature from its pole. In this case the spring may be omitted.

T is a rocking beam, hung upon centers *r*, and so as to rock in a vertical plane—that is, 30 in a plane at right angles to the lever *P*. This beam is provided with a weight, *U*, at one end, and a corresponding weight, *W*, at the other end. These weights are screwed onto the beam, so as to be adjustable, whereby the 35 one, *W*, may be made to slightly overbalance the weight *U*. From the beam or axis on which it turns an arm, *t*, extends up upon that side of the lever *P* toward the stop 3. In its normal position the lever *P* is held against 40 the stop 3 by the spring, and when so held the lever *P* bears against the arm *t*, and holds the beam in the position seen in Fig. 4, with the weight *W* raised. The overbalancing power of the weight *W* is considerably less 45 than the power which holds the lever to the stop 3, and so that the power of the weight is not sufficient to draw the lever from its stop 3. One wire, *R*, is in connection with the beam and weight *W*. As the lever *P* vibrates 50 under the effect of the usual alternating current, its vibrations are so rapid that the beam has not time to turn under the overbalancing power of the weight *W*, that overbalancing power being very light, and gravity only, its 55 movement is naturally extremely slow; but if the lever be drawn to the stop 4 by a continuous current in the proper direction, and there held during the short space of time before mentioned, then the beam will be permitted 60 by the overbalancing power of the weight *W* to turn, causing the weight *W* to descend. It will be understood that the time-signal is a current in such proper direction. Below the weight is a contact-point, 5, with which the 65 other wire, *S*, is connected. The circuit through the wires *R* *S* is therefore open so long as the weight *W* stands away from its

contact 5; but under the continuous current so soon as the weight *W* strikes the contact 5 the circuit is closed through the wires *R* *S*, the 70 said wires *R* *S* being in connection with a clock or other time-signaling device. If with a clock, it may be the usual synchronizing mechanism, which is actuated by the current through the circuit closed by the weight *W* 75 coming upon the contact 5.

The clock-synchronizing mechanism is too well understood to require illustration in this specification, or any suitable or known signal may be employed to give at the station the information as to time. The synchronizing-clock 80 is sufficient for illustration.

In the above illustration of a device whereby under a continuous current the time-signal or standard time is communicated to the several stations on the circuit from the main office, the armature-lever *P* may be understood to be the lever of the usual signaling apparatus, and which carries the hammer at its outer end to strike the bells; but it must 90 be so adjusted as to always normally rest at the same side. The alternating current, which causes the bell-lever to vibrate rapidly, will prevent the beam turning to make contact; but the continuous current over the line will 95 bring the bell-lever to a stand in such position as to permit the weight *W* to make the contact 5; then the standard time is given as before.

While the weighted lever and apparatus 100 which I have described successfully carries out my invention I do not wish to be understood as limiting myself to this or any particular device through which a continuous current will act to make the time-contact, and 105 which will not be affected or caused to operate by the alternating current, as other devices may be substituted therefor—as, for illustration such a device as seen in Fig. 5. In this figure I represents a magnetic needle or lever hung 110 upon a point to swing in a horizontal plane like a magnetic needle, and with which the wire *R* is connected. This lever is free to vibrate on its center in a horizontal plane. 5 represents a contact-point, the same as the contact 5, before referred to, and with which the line *S* is in connection. This contact point is in the path of the lever 6 as it swings in its horizontal plane. 7 represents a coil in the path of the 115 same point of the lever 6 as the contact 5, but upon the opposite side of the lever. 8 represents a stop against which the lever 6 will strike, and so as to prevent actual contact with the pole of the coil 7. The usual alternating currents will hold the south pole of the lever 6 against 120 the stop 8, the break in the alternating currents being too short to permit the repulsion of that south pole; but a continuous current, say, during the before-mentioned short space of time, will repulse that pole or end of 125 the lever 6, causing it to engage the contact 5, as seen in broken lines Fig. 5, and make the circuit the same as did the weight *W*, before described, and so soon as that short space 130

of time has expired, or the continuous current is interrupted, then the lever 6 will be attracted by the coil and return to its stop 8.

It will be understood that the movement of the lever upon its center is so slow or sluggish that the alternating current does not sensibly affect it or cause it to turn upon its center; but the continuous current, being of longer duration, gives the lever time to turn under the repulsive force of such continuous current. This illustration will be sufficient to enable those skilled in the art to adapt other apparatus at the several stations which will be affected by the continuous current to produce the time-signals, but which will not be affected by the ordinary alternating currents used for signaling either the station or the central office.

I have represented the multiple relay as employing two magnets, H H; but it will be understood that one of the magnets may be omitted, it only being essential that the magnet shall be arranged so that its power will bring the several lines into the time-circuit.

Having thus fully described my invention, what I claim, and desire to secure by Letters Patent, is—

1. The method herein described of communicating time-signals over the lines of telephone system, consisting in charging the lines at predetermined intervals with a continuous current from the central office through an apparatus at the several stations affected by such currents to produce certain signals, but not

affected by the ordinary alternating currents used for signaling between the same stations and the main office, substantially as described.

2. The combination, with a telephone system, of a battery, a multiple relay, lines leading from the lines of the telephone-circuits outside the switch-board to said multiple relay, a magnet, armature-lever, and contact-points between which said armature-lever works, one of said contacts making the ground from the switch-board, the other from said battery, and mechanism, substantially such as described, to close and break the circuit through said multiple relay, substantially as specified.

3. The combination, with the lever P, of a polarized relay, the beam T, hung to swing in a plane at substantially right angles to said lever P, the contact end of the beam heavier than its opposite end, the said beam in connection with one wire of a circuit, and a contact in the path of the heavier end of the beam in connection with the other wire, and a device, substantially such as described, between said beam and said lever, whereby in its normal condition said lever will hold the beam from its contact, and under alternating currents prevent the beam from reaching its contact, but under continuous current will permit said beam to turn by its own gravity to make its contact, substantially as described.

ROBERT W. WILLSON.
